UNITED STATES PATENT OFFICE.

FRANK K. SINGER, OF PITTSBURGH, PENNSYLVANIA.

CONVEYING MACHINE.

1,414,220.

Specification of Letters Patent. Patented Apr. 25, 1922.

Application filed March 10, 1921. Serial No. 451,156.

To all whom it may concern:

Be it known that I, FRANK K. SINGER, a citizen of the United States, residing at Pittsburgh, in the county of Allegheny and State of Pennsylvania, have invented new and useful Improvements in Conveying Machines, of which the following is a specification.

This invention relates to a machine for 10 successively conveying and dipping articles into baths containing different liquids. As herein shown and described the invention is used for the purpose of dipping glassware but it will be understood that it is also 15 adapted to be used in connection with other articles and processes.

The primary objects of my invention are to provide a machine of simple and inexpensive construction which will automatically 20 act to perform a series of accurately timed operations. Where my invention is used in connection with operations involving uncomfortably high or low temperatures, or dangerous liquids or gases, the whole operation 25 may be performed within a casing from which the dangerous fumes are extracted and expelled by means of a suitable exhaust fan.

Other objects of the invention consisting 30 of novel features of construction will become apparent on reference to the following specification which describes the invention in connection with the accompanying drawings.

35 In the drawings:—

Figure 1 is a longitudinal vertical section through the casing of the apparatus.

Figure 2 is a section on the line 2—2 of 40 Figure 1, looking in the direction of the arrows.

Figure 3 is a partial plan view and a partial sectional view on the line 3—3 of Figure 1, looking in the direction of the arrows and with the carriers removed.

45 Figure 4 is a perspective detail view of one of the carriers and the corresponding crank arm for the same.

The numeral 10 designates a suitable supporting frame work having on the side 50 members thereof suitable bearings 11 in which is journaled a driving shaft 12 deriving power by means of a pulley 13 secured to one end thereof. The shaft 12 has secured thereto at suitable points driving

worms 14 adapted to mesh with worm wheels 55 15. The worm wheels 15 are secured on transverse shafts 18 which are rotatably mounted in suitable bearings 20 supported on channel beams 21 of the frame-work 10. Crank arms 22, 22' are secured on opposite 60 ends of the shafts 18 and these arms are displaced 180° apart. In initially placing the arms, however, all of the arms 22 and all of the arms 22' are arranged parallel, as shown in Figure 1. Each of the crank arms 22 and 22' are provided at their outer extremity with a pin 23 having a button-like head 24. This head 24 is adapted to engage in a pocket 25 formed on one end of a carrier device which consists of the vertical rod 70 26 having the transverse bar 27 secured to the other end thereof. Spaced pins 28 are secured to and extend from opposite sides of the bar 27 for the purpose of supporting the articles to be treated which in this case are in the form of lamp shades 16 which may be readily suspended from the racks provided by these projecting pins 28. In normal position the rods 26 extend between two channels 30 which form part of the 80 framework of the apparatus and are arranged parallel and slightly spaced apart so that the rods 26 may just readily pass between them. These channels 30 are suitably supported on the frame work by the plates 85 31 riveted to the flanges of the channels and to the side members of the frame 10.

The rod 26 at an intermediate point is provided with a stop composed of an angle plate 32 having one arm attached by suitable fastening devices 33 to the rod and the outstanding arm thereof attached to a plug 29 of suitable resilient material, such as rubber. This stop is so positioned relatively 90 to the circular path traced by the pin 23 as 95 to rest upon the upper flanges of the channels 30 before the revolving crank arms 22, 22' have reached the lower limit of their paths. This causes the carrier to be deposited upon the channel bars until the next 100 rotating arm engages the pocket 25, picks up the carrier and moves it to the next position. Suitable receptacles 34, 35 and 36 and 34', 35' and 36' correspond in location 105 to the successive positions of the carriers as they are deposited on the channels by the rotating arms 22, 22'. These receptacles provide baths of different liquids in which

the articles supported by the carriers are immersed for certain periods of time depending upon the speed of the rotation of the crank arms. The receptacles 34, 35, and 36 are located within a closed casing 37 having openings 38 and 39 in the end walls through which the carriers may pass in introducing the articles into the casing and removing them from the casing respectively.

10 The upper part of the casing is closed by a cover plate 40 which is provided only with narrow slots 41 for the purpose of permitting the passage of the rods 26 therethrough. In case liquids, or gases are used 15 which give off dangerous or offensive fumes, means are provided for exhausting these fumes and gases out of the casing so as to prohibit their escape into the atmosphere of the room where the machine is operating, 20 and for this purpose the exhaust pipe 42 is used having the exhaust fan 43 mounted therein and rotated by power from any suitable source (not shown). The exhaust pipe 42 is provided with branches 44 and 45 25 which open into an extension of the outlet opening 39 so that the gases may be drawn off without interfering with the regular operation of removing the carriers from the casing.

30 In order that the operation of my invention may be clearly understood I have indicated the different positions of the carriers by the positions A, B, C, D and E. The carriers containing the articles to be treated 35 are first positioned on the channels 30 so that the pocket 25 of the carrier will be in position to be engaged by the button 24 of a crank arm 22. When this occurs the carrier is lifted from the channels, passed 40 through the opening 38, and as the rotation of the arm continues the stop 29 encounters the channels 30 at the position B whereupon the articles are suspended in the bath 34. In the mean time, however, the next crank 45 arm has revolved to such position as to pick up the carrier at the position B and transport it to the position C where it is deposited on the channels 30 and the articles are suspended in the receptacle 35. After 50 a short period the next succeeding crank arm engages the carrier and transfers the same in a circular path until it reaches the position D wherein the carrier is suspended into the receptacle 36. From this 55 position the crank arm 22 of the last transverse shaft 18 engages the carrier and lifts it through the outlet opening 39 and deposits the carrier on the channels in the position E, from which the same may be removed in 60 any desired manner.

It is believed that from the above description, it is apparent that my device provides an apparatus for automatically submitting articles of glassware or other material to a succession of operations all of which

are accurately timed to secure the best and uniform results. This being accomplished in a simple and inexpensive manner without involving any danger or discomfort to those operating the machine.

70

Having thus described my invention what I claim as new and desire to secure by Letters Patent, is:—

1. In a dipping machine, the combination of a plurality of carriages, and rotatable arms arranged to successively advance a carrier from one location to another, said arms being initially arranged in parallel relation and rotating in synchronism so as to provide a simultaneous advance for all the carriers passing through the machine.

75

2. In a mechanical conveying apparatus, a carrier for holding the material to be treated, a plurality of baths in which the material is adapted to be immersed for definite time intervals, and rotatable arms so arranged as to advance said carrier from one bath to the other automatically and progressively.

80

3. In a mechanical conveying machine, a carrier having a device on the upper end thereof, a series of rotatable arms, means on each of said arms adapted to engage said device and advance the carrier from one point to another.

85

4. In a machine for dipping articles, a carrier comprising a rod having a pocket at one end, means for supporting the articles at the other end of said rod, and a stop on said rod, a plurality of baths, and means adapted to engage said stop for releasing the carrier from one of said rotating arms and suspending said articles in one of said baths until the next adjacent arm engages said pocket and transfers the carrier to a position corresponding to the succeeding bath.

90

5. In a machine for dipping wares, a plurality of carriers, a casing containing a plurality of baths and having inlet and outlet openings formed therein, arms adapted to rotate arranged to engage said carriers and successively advance each carrier from a loading point outside the casing, through said inlet opening, to the baths successively, and through the outlet opening to the delivery point.

95

6. In a machine for dipping wares, a plurality of carriers, a casing containing a series of baths and having inlet and outlet openings formed therein, arms adapted to rotate arranged to engage said carriers and successively advance each carrier through the inlet opening, to the baths successively, and through the outlet opening, and apparatus for exhausting from the casing fumes arising from said baths.

100

7. In a conveying machine, a carrier comprising a rod having a pocket at one end, a support for articles to be treated at the other end, and a stop secured thereto, bars adapt-

130

ed to engage said stop but spaced apart sufficiently to allow said rod to pass between them whereby carriers are successively deposited on said bars at certain points for 5 subjecting the articles carried by said supports to a series of operations.

In testimony whereof I have hereunto set
